No. 834,497.

PATENTED OCT. 30, 1906.

H. SHOEMAKER.
TRANSMITTING APPARATUS.
APPLICATION FILED JAN. 2, 1906.

FIG.1.

FIG. 2.

FIG. 3.

FIG. 4.

FIG. 5.

UNITED STATES PATENT OFFICE.

HARRY SHOEMAKER, OF JERSEY CITY, NEW JERSEY, ASSIGNOR TO
INTERNATIONAL TELEGRAPH CONSTRUCTION COMPANY, A COR-
PORATION OF NEW YORK.

TRANSMITTING APPARATUS.

No. 834,497.

Specification of Letters Patent.

Patented Oct. 30, 1906.

Application filed January 2, 1906. Serial No. 294,040.

To all whom it may concern:

Be it known that I, HARRY SHOEMAKER, a citizen of the United States, residing at Jersey City, in the county of Hudson and State 5 of New Jersey, have invented a new and useful Transmitting Apparatus, of which the following is a specification.

My invention relates to telegraph transmitting apparatus, and more particularly to 10 means for controlling the operator's key.

My invention resides in apparatus for minimizing sparking at key-contacts, especially when the key is required to control an alternating or fluctuating current and when such 15 current is of considerable magnitude, as in the case of telegraph systems employing electroradiant energy and commonly known as "wireless-telegraph" systems.

In some telegraph systems, especially wireless-telegraph systems, the operator's key is required to control or interrupt considerable energy with certainty and clearness. Large currents cause danger of destruction of the key-contacts by arcing or sparking. To this 20 end I associate with the operator's key an electromagnet connected either in series with or in shunt to the circuit controlled by the key, such magnet operating to retain the key in closed position until the alternating or fluctuating current reaches or nearly reaches its 25 minimum value.

For several of the forms my invention may take reference is to be had to the accompanying drawings, in which—

35 Figure 1 is a side elevational view, partly in section, of a telegraph-key and an associated electromagnet. Fig. 2 is a vertical elevational view, partly in section, taken at right angles to Fig. 1. Fig. 3 is a diagrammatic view of simple transmitting-circuits involving an electromagnet associated with the key having its winding in series with the circuit controlled by the key. Fig. 4 is a view 40 similar to Fig. 3, except that the electromagnet-winding is connected in shunt to the circuit controlled by the key. Fig. 5 is a fragmentary diagrammatic view showing a modification of Fig. 4.

50 Referring to Fig. 1, K is an operator's key pivoted at 1 and having the usual finger-button 2. A spring or other means (not shown) serves to keep the key in open-circuit position, as is well understood and common in

telegraphy. The key-contacts are shown at 3 and 4.

55 5 is an iron armature, preferably laminated, secured to the under side and extending transversely of the key-bar K.

60 6 are vertically-extending magnet-cores having the common yoke or back armature 7, the latter resting upon the adjusting-screw 8, passing through a member 9, constituting a portion of or a fixture to the frame in which the bar K is pivoted. Embracing each core 6 is a closed-circuited winding or circumferentially-continuous tube 10, of copper or other well-conducting material. The tubes 65 10 may terminate in flanges 11, which may serve both to radiate any excessive heat that may be generated in the tubes 10 and as a 70 winding-space for the windings 12 12, which may be either series or shunt windings, as hereinafter described.

75 In Fig. 3, simply by way of example, a simple wireless-telegraph transmitting apparatus is shown, and applied thereto is my invention. A represents a simple aerial conductor, between which and the earth connection E is a spark-gap g. Bridging the spark-gap is the secondary S of a step-up transformer whose primary is shown at P. In series with the primary P is the generator or source of electricity G, preferably an alternating-current generator. For long-distance working considerable energy must be delivered 80 by the generator G and must be controlled by the key at its contacts 3 and 4, which are also connected in series with the primary P and with the winding 12 of the electromagnet. The conducting-tubes 10 10 are shown 85 diagrammatically only. When the key K is depressed by the operator, the current flows through the winding 12 and the primary P in series, causing sparks at the gap g and the radiation of electroradiant energy from A. In 90 so depressing the key the armature 5 has been brought within the range of action of the poles of the cores 6 6 and attracted thereby, thus, in effect, assisting the operator in holding the key down in circuit-closed position. Remembering, however, that the current in the 95 circuit of the key is an alternating one or a fluctuating one, it may occur, as it does frequently in practice, that the operator will remove the pressure from the key at an instant of time when the current in the circuit 100 105 110

is at or near its maximum, or at any rate at a value considerably greater than zero. In the absence of the electromagnet, as here shown, the key would open at the instant the 5 operator removed the pressure, with resultant spluttering and arcing at the contacts 3 and 4, due to the fact that at that instant the current is of considerable magnitude. This 10 arcing and spluttering soon destroys the efficiency of a key, requiring its replacement or at least interfering with the transmission of clear sharp signals. By the use of the electromagnet, however, the key is held over an interval of time after the operator may 15 have released pressure when the current is at a considerable value. When the current reaches or approximately reaches its minimum value, however, the strength of the magnet is correspondingly reduced and releases the key at the instant of small or zero 20 value, with the result that practically no arcing occurs at the contacts 3 and 4. This means that such contacts are not damaged, have a long life, and that the signaling is and 25 continues to be clear and sharp.

Since the windings 12 12 upon the cores 6 6 are inductive ones in the relation shown, the current lags behind the impressed electromotive force, as is well understood in the art 30 of alternating currents. The closed-circuited winding or circumferentially-continuous tubes 10 10 serve as closed secondaries and tend to bring the current and electromotive force more nearly into phase—that is, they 35 tend to shift the phase of the magnetism.

In Fig. 4 the arrangement is similar to that in Fig. 3, except that the key, the generator G, and primary P are in series with each other, no electromagnet-winding being series 40 in this case. However, the magnet-winding 12' upon the core 6 is connected in shunt to the circuit controlled by the key, so that the key controls the circuit of the magnet 12' as well as that of the primary P. In this case 45 the number of turns upon the magnet is greater than in the case of Fig. 3, and the self-induction is also considerably greater. To shift the phase of the current with respect to the electromotive force in the coil 12', the 50 circumferentially-continuous tubes 10 10 operate as closed secondaries. The adjustable or suitable condenser C may be connected in series with the winding 12' to bring the current more nearly in phase with the 55 electromotive force or to otherwise shift the current phase or the phase of the magnetism. Either the condenser C or the tubes 10 10 may be used separately and independently or all may be used conjointly.

60 In Fig. 5 the arrangement is similar to that in Fig. 4, except that the condenser C is connected in shunt to the magnet-winding 12'.

By the apparatus herein described the 65 operator's key, if not released by the oper-

ator at or near the instant of minimum current in the circuit, is held over by an electromagnet and then released by the magnet at or near the instant of minimum current, with resultant reduction of arcing or sparking, as 70 heretofore described.

By adjusting the screw 8 the electromagnet may be caused to approach or recede from the armature 5, thus giving an advantageous adjustment for the control exercised 75 by the electromagnet.

What I claim as new, and desire to secure by Letters Patent of the United States, is—

1. In a telegraph-transmitter, an operator's key, a source of alternating or fluctuating current, an electromagnet operating upon said key, the winding of said magnet being connected in shunt to the circuit controlled by said key, whereby said key is permitted to return to normal position only at 85 or near the instant of minimum current.

2. In a telegraph-transmitter, an operator's key, a source of fluctuating or alternating current controlled by said key, an electromagnet associated with said key for 90 permitting its return to normal position only at or near the instant of minimum current and a phase-shifting device associated with said electromagnet.

3. In a signaling system, an operator's 95 key, a source of fluctuating or alternating current controlled by said key, an electromagnet associated with said key for permitting its return to normal position only at or near the instant of minimum current, and a closed-circuited winding associated with the winding of said electromagnet.

4. In a signaling system, an operator's key, a source of fluctuating or alternating current controlled thereby, an electromagnet 105 associated with said key for permitting its return to normal position only at or near the instant of minimum current, and a condenser associated with the winding of said electromagnet. 110

5. In a wireless signaling system, a radiating-conductor, a source of fluctuating or alternating current for supplying energy thereto, an operator's key for controlling said energy, an electromagnet associated with said key for permitting its return to normal position only at or near the instant of minimum current, and a phase-shifting device associated with the winding of said electromagnet. 115

6. In a wireless signaling system, a radiating-conductor, a source of fluctuating or alternating current for supplying energy thereto, an operator's key for controlling said energy, an electromagnet associated with said key for permitting its return to normal position only at or near the instant of minimum current, and a closed-circuited winding associated with the winding of said electromagnet. 125

7. In a wireless signaling system, a radiat- 130

- ing-conductor, a source of fluctuating or alternating current for supplying energy thereto, an operator's key for controlling said energy, an electromagnet associated with said key for permitting its return to normal position only at or near the instant of minimum current, and a condenser associated with the winding of said electromagnet.
8. In a wireless signaling system, a radiating-conductor, a source of fluctuating or alternating current for supplying energy thereto, an operator's key for controlling said energy, and an electromagnet, having its winding connected in shunt to the circuit controlled by said key, for permitting the return of the key to normal position only at or near the instant of minimum current.
9. In a wireless signaling system, a radiating-conductor, a source of fluctuating or alternating current for supplying energy thereto, a key for controlling said energy, an electromagnet associated with said key for holding it closed until at or near the instant of minimum current, and a closed circuit associated with the magnetic circuit of said magnet.
10. In a wireless signaling system, a radiating-conductor, a source of fluctuating or alternating current for supplying energy thereto, a key for controlling said energy, an electromagnet associated with said source of energy and key for holding said key closed until at or near the instant of minimum current, and a conducting-sleeve associated with the magnetic circuit of said magnet.
11. In a wireless signaling system, a radiating-conductor, a source of fluctuating or alternating current for supplying energy thereto, a key for controlling said energy, an electromagnet associated with said key for holding it closed until at or near the instant of minimum current and a phase-shifting device associated with a winding of said magnet.
12. In a wireless signaling system, a radiating-conductor, a source of fluctuating or alternating current for supplying energy there-
- to, a key for controlling said energy, an electromagnet associated with said key to hold it closed until at or near the instant of minimum current, a winding of said magnet being connected in shunt to the circuit including said source of energy, and a phase-shifting device associated with said winding.
13. In a wireless signaling system, a radiating-conductor, a source of fluctuating or alternating current for supplying energy thereto, a key for controlling said energy, an electromagnet associated with said key to hold it closed until at or near the instant of minimum current, a winding of said magnet being connected in shunt to the circuit including said source of energy and controlled by said key, and a phase-shifting device associated with said winding.
14. In a wireless signaling system, a radiating-conductor, a source of fluctuating or alternating current for supplying energy thereto, a key for controlling said energy, and an electromagnet associated with said key for holding it closed until at or near the instant of minimum current, a winding of said magnet being connected in shunt to the circuit including said source and controlled by said key.
15. In a wireless signaling system, a radiating-conductor, a source of fluctuating or alternating current for supplying energy thereto, a key for controlling said energy, an electromagnet associated with said key to hold it closed until at or near the instant of minimum current, a winding of said magnet being connected in shunt to the circuit including said source of energy, and a closed circuit and a condenser associated with said magnet-winding.

In testimony whereof I have hereunto affixed my signature in the presence of the two subscribing witnesses.

HARRY SHOEMAKER.
